COMBINED PACKAGING AND DISPLAY CONTAINER

Martin Nathan Kaplan, 11610 Canfield St.,
North Hollywood, Calif. 91605

Filed May 19, 1972, Ser. No. 255,308

Term of patent 14 years

Int. Cl. D9—03

U.S. Cl. D9—191

FIG. 1 is a perspective view of a combined packaging and display container showing my new design;

FIG. 2 is a front elevational view on a reduced scale; and

FIG. 3 is a side view thereof.

I claim:

The ornamental design for a combined packaging and display container, as shown.
